UNITED STATES PATENT OFFICE.

ISAAC WAGEMAKER, OF GRAND RAPIDS, MICHIGAN.

DRAWER SLIDE.

1,410,629.

Specification of Letters Patent. Patented Mar. 28, 1922.

Application filed June 27, 1919. Serial No. 307,211.

To all whom it may concern:

Be it known that I, ISAAC WAGEMAKER, a citizen of the United States of America, residing at Grand Rapids, in the county of Kent and State of Michigan, have invented certain new and useful Improvements in Drawer Slides; and I do hereby declare the following to be a full, clear, and exact description of the invention, such as will enable others skilled in the art to which it appertains to make and use the same.

This invention relates to drawer slides and has for its primary object and purpose the construction of a slide which is very simple yet effective to carry a drawer practically entirely outside of its enclosing case or cabinet, the slide having a progressive movement back and forth with the drawer so that when said drawer is wholly extended, the slides, one at each side of the drawer are extended one half of their length. A further object of the invention is to make a metal construction of drawer slide and provide it with a novel form of progressive movement construction, very simple in structure but one in which the action of the slide is especially smooth and easy. These features as well as many others not at this point specifically outlined will appear fully and in detail as understanding of the invention is had from the following description, taken in connection with the accompanying drawings, in which,

Fig. 1 is a partial section and side elevation illustrating the construction and extension of the drawer slide, the drawer being indicated in dash outline that the slide construction may more fully appear.

Fig. 2 is a partial section and plan showing one slide partially extended.

Fig. 3 is a side elevation of a drawer used with the slide.

Fig. 4 is an enlarged fragmentary vertical transverse section through a drawer slide and adjacent portions of the drawer and supporting framework of the case or cabinet, and

Fig. 5 is an enlarged side view of the rear portion of the slide.

Like reference characters refer to like parts in the different views of the drawings.

The drawers may be carried by and enclosed in any suitable case or cabinet, and in the construction shown side frames comprised of front and rear vertical bars 1 con-

nected by horizontal bars 2 are used, being spaced apart and connected together by horizontal cross frames made up of transverse bars 3 connected by side bars 4. This frame work may be enclosed by panels such as that shown at 5 at the back, and any suitable side panels if desired, leaving the front open for the insertion of the drawers.

The number of drawers in a case is a matter of choice, and the construction of the slides therefor for one applies to all. A channel member 6 is located horizontally above each side 4 of the transverse frames and against the horizontal members 2 of the cabinet side frames, the flanges of said channel member extending from the web thereof toward said bars 2. The upper flange has a part at its free edge cut away thus making a slot 7 which extends the entire length of the channel. Inside of the channel member at its front end is a bar 8 of wood. This bar extends back substantially one half of the length of the channel member and is held in place by screws 9. A part of the bar 8 directly below the slot 7 is removed forming a groove as shown in Fig. 4.

A slide of metal is located directly above the channel bar. The slide is formed of sheet metal and has a lip 10 at its lower edge which extends through the slot 7 in the channel 6 and rides in the groove in bar 8. At its rear end the slide has an integral downward projection 11 which also passes through the slot 7 and on which a roller 12 is rotatably mounted, the same being within the channel member and designed to traverse the length thereof until stopped by coming against the rear end of the bar 8, thereby limiting the extension of the slide in front of the case to about one half of its length.

Above the lower lip 10 of the slide a section 13 is pressed to come partially over the channel 6. A roller 14 is mounted on this section at the front end of the slide and a second roller 15 is rotatably mounted at about the middle point in the length of the slide on said section 13, the rollers being positioned so as to ride on the upper flange of the channel member 6. Above the section 13, another section 16 is formed lengthwise of the slide and pressed so as to lie in the same vertical plane with the lower lip 10. Above section 16, a section 17 is formed, being pressed inwardly so as to lie in a plane

intermediate that of sections 13 and 16, while above section 17, still another section 18 is formed lying in the same plane with section 16 and lip 10. A horizontal ledge 19 is turned inwardly from the upper edge of section 18 for a distance, from the inner edge of which an upper lip 20 is turned, its inner side lying in the same plane as the inner sides of the rollers 14 and 15 and adapted to come against or very close to the sides of the drawer carried by two of the slides, one being located at each side of the case or cabinet.

The drawer is of usual construction including sides 21 to which angle bars formed of vertical legs 22 and projecting horizontal legs 23 are secured, one at each side of the drawer. The leg 23 is curved downwardly from the rear end toward the middle, as shown in Fig. 3, the curve being for substantially one half the length of the leg, the forward portion being straight. A roller 24 is mounted at the rear end of the leg 22 and is designed to bear against the under side of the ledge 19 while rollers 14 and 15 come immediately below the leg 23, which bears on them.

A plate 25 is attached to each side 21 of the drawer above the angle and a dog 26 is pivotally connected at its upper end thereto, riding on the upper sides of the ledges 19 of the two slides, as the drawer is drawn out. Near the front end of each slide a stop 27 is cut and turned from the upper lip 20, and over the ledge 19. The dogs coming to said stops when the drawer is drawn out, serve to limit the outward movement of the drawer and prevent disengagement of the drawer from the slides. The dogs 26 may be readily lifted, however, whenever it is desired to entirely remove the drawer.

This construction is relatively simple and may be manufactured at low cost, the parts being all of sheet metal readily rolled, cut and formed into shape. As the drawer is pulled out, the leg 23 rides against roller 15 causing the same to turn and move along the upper flange of channel 6, whereby the slide at each side of the drawer moves forward carrying the drawer forward at the same time the drawer is being drawn forward with respect to the slide. The weight of the drawer and contents is transmitted to the drawer slides through rollers 15 and 24 and from the slides to the channels 6 through rollers 12 and 15. Roller 12 runs on the upper and lower flanges of the channels 6, serving a double function depending on the position of the drawer, keeping it from tipping when extended and supporting the same when within the case. The formation of the slides with various sections 13, 16, 17 and 18 set off into different vertical planes makes a compact structure in which the rollers cannot move laterally, it being

clear that roller 24 is disposed between the leg 22 and section 17 and rollers 14 and 15 between the sides of the drawer and sections 13 of the slide, the offsets of said sections being just sufficient to let the rollers pass freely but allowing no lateral movements. The progressive movements of the slides with the drawer is a feature of novelty and merit and such movements are very effectively and practically accomplished. The drawer has an exceptionally smooth and easy movement. The placing of the drawer between the slides is automatically accomplished, the dogs rising and riding over stops 27 and then dropping behind them. The construction is practical in every respect.

I claim:

1. In combination, a support, a horizontally positioned metal channel member attached to the support, the upper flange of the channel member having a portion cut away at its free edge to form a slot lengthwise of the member, a slide formed from a plate of sheet metal located above the channel member and having a lower tongue entering the slot in the channel member and a depending projection at the rear lower part of said slide extending through the slot, a roller on said projection within the channel member, rollers on the slide at the front end and middle thereof riding upon the upper flange of the channel member, a drawer, and means attached to a side of the drawer to bear on said middle roller and progressively move the slide forward as the drawer is moved forward, substantially as described.

2. In combination, a support, a pair of horizontal channel members carried by the support in spaced apart relation, a slide located above each channel member, front and intermediate rollers attached to each slide and adapted to run on the upper flange of the channel member, interengaging means between the rear end of each slide and its associated channel member, a drawer positioned between the slides, and a horizontal leg attached to each side of the drawer and adapted to ride on the rollers on the slides at the sides of the drawer, each of said legs being curved slightly in a downward direction from the rear end to the middle thereof, substantially as and for the purposes described.

3. In combination, a drawer, a movably mounted slide at each side thereof, an angle member attached to each side of the drawer and each having an outwardly extending horizontal leg curved downwardly slightly from its rear end toward the middle thereof, front and intermediate rollers on each slide to carry the drawer, said horizontal legs riding on the rollers, and tracks, one for each slide on which the intermediate rollers turn as the same are driven on drawing the

drawer forward and moving said horizontal legs over and against said rollers, substantially as described.

4. In combination, a drawer, a sheet metal angle member attached lengthwise of and at each side of the drawer, each angle member having an outwardly projecting horizontal leg slightly curved downwardly from its rear end toward its middle, rollers on which 10 said legs ride, a slide on which said rollers are rotatably mounted, and a track for each slide on which the rollers bear, each slide also having means at its rear end engaging with and rolling on the under side of its 15 associated track, substantially as described.

5. In combination, a drawer, an angle member attached lengthwise of and at each side of the drawer, each having an outwardly projecting horizontal leg, slightly curved 20 downwardly from its rear end toward the middle thereof, a slide at each side of the drawer, tracks to carry the slides, and means on the slides running on said tracks and on which the said legs of the angle members 25 bear, whereby the slides are progressively moved in a forward direction with forward movement of the drawer, substantially as described.

6. A slide for drawers formed from sheet 30 metal and comprised of a downwardly extending lip at its lower edge, a projection at the rear lower portion of the slide projecting below the lip, a roller mounted at one side of the projection, a longitudinal 35 section pressed in the slide above the lower lip and slightly over the roller, two rollers mounted on the slide in the length of said section, one at the front end thereof and the other adjacent the middle of the section, 40 a second section disposed longitudinally of the slide in the same plane as the lip, a third section longitudinally disposed in the slide above the second section and in a plane between the first and second sections, an upper 45 section above the third section in the same plane as the lower lip and second section, a horizontal ledge turner from the upper section over all of the rollers, and an upper

lip disposed longitudinally of the slide at the edge of said legs, said lip having a stop 50 tongue struck therefrom over the ledge at the front end of the slide, substantially as described.

7. A drawer having sides, and an angle member disposed lengthwise of and between 55 the upper and lower edges of each of said sides, said member comprising a vertical leg lying against a side of the drawer and attached thereto and a horizontal outwardly extending leg curved slightly downwardly 60 from its rear end to the middle, substantially as and for the purposes described.

8. A drawer having sides, an angle member disposed lengthwise of and between the upper and lower edges of each of said sides, 65 said member comprising a vertical leg lying against a side of the drawer and attached thereto and a horizontal outwardly extending leg curved slightly downwardly from its rear end to the middle, and a dog pivotally 70 connected to each side of the drawer above the said member, and substantially midway between the ends of the drawer.

9. In combination a support, parallel horizontal spaced apart tracks on the support, 75 said tracks being of channel formation with upper and lower flanges extending outwardly, a drawer disposed between the tracks, a slide at each side of the drawer, each having a lower lip passing by the outer 80 edge of the upper flange of the track below it, a projection at its rear end extending into the track and an inturned horizontal ledge at its upper portion extending the full length of the slide, a roller on the projection within 85 the track, front and intermediate rollers on each slide running on the upper flange of each track, an angle member attached to each side of the drawer, each having an outturned horizontal leg riding on said front and intermediate rollers, and a roller at the rear end of each angle member bearing on the under side of each ledge of each slide, substantially as described.

In testimony whereof I affix my signature. 95
ISAAC WAGEMAKER.
